UNITED STATES PATENT OFFICE.

DUDLEY E. MURRAY, OF ROANOKE, INDIANA.

GAS-DISTRIBUTING MECHANISM.

1,140,278.

Specification of Letters Patent. Patented May 18, 1915.

Application filed June 15, 1914. Serial No. 845,926.

To all whom it may concern:

Be it known that I, DUDLEY E. MURRAY, a citizen of the United States, residing at Roanoke, in the county of Huntington and State of Indiana, have invented certain new and useful Improvements in Gas-Distributing Mechanism, of which the following is a specification.

The object of my invention is to provide a mechanism which may be used to control the inlet and exhaust of a gas engine and which is so constructed that a uniform efficiency of results is accomplished at all times.

A further object is to so construct the mechanism that a single port may be used for the intake and the exhaust and that this port will be opened at the proper time to admit the charge to the cylinder, will then be closed during the compression and firing cycles of the engine and will be again opened to permit the exhaust of the burnt gases.

Yet another object is to so construct the mechanism that the necessity for the use of separate valves to control the intake and the exhaust to the engine is obviated and the opening of the port for the intake and the exhaust is accomplished gradually, likewise the closing of the port at the end of each of these cycles.

With other objects in view, which will be referred to, my invention consists in the peculiar combination and novel arrangement of parts, such as will be hereinafter more fully described in connection with the accompanying drawings and more particularly pointed out in the appended claims.

In the drawings:—Figure 1 is a view in vertical section through the upper end of the cylinder of a gas engine with my invention applied thereto. Fig. 2 is a horizontal sectional view on the line 2—2 of Fig. 4. Fig. 3 is a vertical sectional view on the line 3—3 of Fig. 4. Fig. 4 is a transverse vertical sectional view through the case and the operating cylinder of the mechanism.

The mechanism comprises the case 1 which is adapted to be connected with the cylinder 2 of the engine at a point over the inlet and exhaust port which is positioned to communicate with the explosive chamber of the cylinder and in Fig. 1 is indicated by the dotted lines at 3, as extending through the

cylinder head. This case 1 may be secured to the cylinder in any desired manner and a passage 4 formed through the wall thereof will establish communication with the opening or port 3 provided in the cylinder 2 to act as a common inlet and exhaust port. A gas-supply pipe 5 is secured in the opening 6 through the case 1 which opening is preferably located at a point diametrically opposite to the opening 4 and slightly offset therefrom in the direction of the longitudinal extent of the case. A cylinder 7 is revolvably mounted within the case 1, a shaft 8 being connected with this revolvble cylinder and provided with a gear 9 to mesh with the gear 10 secured on the shaft 11 which may be turned by gear intermeshing with gear on the crank shaft or in any suitable manner to travel with and have its speed regulated by the speed of revolution of the crank shaft, the manner of making this connection will be perfectly obvious and is therefore not shown in the present disclosure.

A gas duct 12 is provided entirely around the cylinder 7 in that portion which turns adjacent the opening 6 and as stated, the opening 6 and the opening 4 are so offset that the opening 4 has no normal communication with this gas duct 12. An arm or branch 13 is provided from the gas duct 12 to extend to a position that it revolves adjacent the opening 4 through the case 1, and as shown in Figs. 3 and 4, when this branch 13 is turned to a position to cover the opening 4 communication is established from the gas-supply pipe through the gas duct 12 and this branch to the interior of the engine cylinder 2. A part of the wall of the cylinder 7 is cut away to form a passage at 14, which passage is in alinement with the branch 13 from the gas duct 12 and is preferably placed just in advance thereof, as better disclosed in Fig. 4. By placing the passage 14 in this relation, the engine is permitted to exhaust from the end of a firing cycle to the commencement of the intake cycle and the cylinder is thus scavenged of all burnt gas before the new charge of explosive mixture is introduced thereto.

In use, the intake to the explosion chamber is continued during the length of time that it takes the cylinder 7 to move in that

2
part indicated between the lines *a* and *b* to pass the opening 4 which communicates with the explosion chamber, the compression period within the explosion chamber will continue during the length of time that the cylinder 7 requires to move that part of its circumference indicated between the lines *b* and *c* to pass the opening 4, the firing cycle will extend from the passage of the points indicated at *c* to the point at *d*, and from this point indicated at *d* to the point indicated at *a* the burnt gases will be permitted to exhaust from the explosion chamber through the openings 3, 4, and the passage 14 10 to prepare the explosion chamber for the new charge which is to be admitted immediately upon the completion of the exhaust action.

From the foregoing, it will be seen that I have provided a mechanism adapted to be attached around a port formed through the cylinder of a gas engine to communicate with the explosion chamber thereof and to form a common intake and exhaust port, which mechanism is so arranged that communication is established between said port and a gas-supply pipe connected with the mechanism at the proper intake interval, the port is closed during the compression and firing interval, and the port is again opened to permit the exhaust subsequent to the firing cycle of the engine, further it will be seen that the mechanism is positive in its operation and that there is a gradual opening and closing of the port establishing communication with the explosion chamber on both the intake interval and the exhaust interval.

While I have herein shown and described one specific form of my invention, it will be understood that slight changes might be made in the form and arrangement of the several parts without departing from the spirit and scope of my invention, and hence I do not wish to be limited thereto except for such limitations as the claims may import.

I claim:

1. A mechanism to be used in connection with a gas engine comprising a case connected to have communication with the explosion chamber, an explosive mixture supply connected with said case, a cylinder revolvably mounted in said case and connected to have turning movement during the normal operation of the engine, a duct formed around the periphery of said cylinder to be at all times in communication with the explosive mixture supply, and a branch provided from said duct to register with the communicating passage to the explosion chamber as the cylinder is turned and to thus permit the supply of the explosive mixture from the duct to supply the engine.

2. A mechanism to be used in connection with a gas engine having a common intake

and exhaust port comprising a case constructed to be connected adjacent said ports and having an opening to establish communication therewith, an explosive mixture supply connected with the case, a cylinder revolvably mounted in the case, a duct formed around said cylinder to be at all times in communication with said explosive mixture supply, a branch provided from said duct to come into registry with the port as the cylinder is turned, an exhaust passage provided in said cylinder, and means connected to cause a turning of said cylinder during the normal operation of the engine.

3. A mechanism to be used in connection with a gas engine having a common inlet and exhaust port comprising a case constructed to be secured adjacent this port and provided with an opening to establish communication therewith, a cylinder rotatably mounted within the case, an explosive-mixture supply connected with the case, a duct provided to extend around the periphery of the cylinder at a point to be at all times in communication with the explosive mixture supply and having a branch formed to extend in the direction of the longitudinal extent of the cylinder to establish communication between the duct and the port at the proper intake interval as the cylinder is turned, and an exhaust passage formed in the cylinder to establish communication from the port to the exhaust as this cylinder is given a further turning movement.

4. A mechanism to be used in connection with a gas engine comprising a case constructed to be secured adjacent the intake port to the engine and provided with an opening to establish communication therewith, a cylinder made in the form of an open ended ring mounted in said case to be capable of revolvable movement, an explosive mixture supply connected with the case adjacent the mounting of said cylinder, a duct provided peripherally around said cylinder to be at all times in registry with said explosive mixture supply, and a branch provided from said duct to open communication to the intake port as the cylinder is turned at the proper intake interval.

5. A mechanism to be used in connection with a gas engine having a common intake and exhaust port comprising a case to be secured adjacent this port and provided with an opening to establish communication therewith, a cylinder revolvably mounted within the case, an explosive-mixture supply connected with the case at a point opposite and offset in the direction of the longitudinal extent of the case from the opening establishing communication to the port, a duct provided peripherally around the cylinder to be at all times in communication with the explosive-mixture supply

and provided with a branch to be brought into communication with said port as the cylinder is turned, an exhaust passage provided in the cylinder adjacent said branch 5 from the duct, and means to be connected with the moving parts of the engine to cause the cylinder to be turned to bring said fluid-supply duct and said exhaust passage into

registry with said port at the proper intervals.

In testimony whereof I affix my signature 10 in presence of two witnesses.
